UNITED STATES PATENT OFFICE.

WILLIAM C. APGAR, OF ALLIANCE, OHIO.

AUTOMATIC FILLING STATION.

Application filed March 11, 1925. Serial No. 14,812.

This invention aims to provide a novel dispensing means for a gasoline tank, or other tank of a similar sort.

It is within the province of the disclosure 5 to improve generally and to enhance the utility of devices of that sort to which the invention appertains.

Although a preferred form of the invention has been delineated in the drawings, it 10 will be understood that a mechanic, working within the scope of what is claimed, may make changes in the precise form shown, without departing from the spirit of the invention.

15 In the accompanying drawings:—

Figure 1 shows in elevation, a device constructed in accordance with the invention; Figure 2 is a cross section taken about on the line 2—2 of Figure 1; Figure 3 is a section 20 taken about on the line 3—3 of Figure 1; Figure 4 is a longitudinal section, wherein parts appear in elevation, parts being broken away; Figure 5 is a sectional elevation showing a portion of the combined inlet and overflow 25 pipe, and sundry elements which are associated therewith; Figure 6 is a fragmental elevation wherein parts are broken away; Figure 7 is a transverse section taken about on the line 7—7 of Figure 4, parts being omitted; 30 Figure 8 is a view disclosing the stop lever.

In carrying out the invention, there is provided a support, in the form of a hollow pedestal 1, having a door 2 giving access to those parts of the machine which are within the 35 pedestal, the door 2 being held closed by a lock 3. The pedestal 1 carries an upper bracket 20 and a lower bracket 30.

The pedestal 1 is surmounted by a measuring tank 4, the bottom 5 of which forms the 40 top of the pedestal 1. The tank 4 is inscribed with a vertical scale 6, indicating gallons or any other unit of measure.

The numeral 7 designates an air suction pipe located in the pedestal 1 and extended 45 upwardly through the brackets 20 and 30 into the tank 4. A slowly closing three-way control and vent valve 8 is interposed in the suction pipe 7 and is operated by a lever 9 fulcrumed at one end on the casing of the valve 50 8. A weight 10 is adjustable longitudinally of the lever 9, the outer end of the lever operating within a vertical trough-shaped guide 11 located in the pedestal 1 and supported thereby.

55 The combined supply and overflow pipe is designated by the numeral 12 and extends up-

wardly through the brackets 30 and 20, as shown in Figure 5, the upper end of the pipe 12 being assembled with the bottom 5 of the tank 4. A slidable section 14 is adjustable 60 vertically in the upper end of the pipe 12 and is suitably packed, as shown at 15, to prevent leakage where the section 14 passes through the bottom 5 of the tank 4.

The means for adjusting the slidable section 14 vertically comprises a rack bar 16 slidably mounted at 19 in the brackets 20 and 30, and including a stem 17 operating in a gland 18 on the bottom 5 of the tank 4, the upper end of the stem 17 being connected by a cross 70 arm 46 with the upper end of the pipe section 14. The rack bar 16 meshes with a pinion 21 journaled on the bracket 30 and supplied with a handle 22.

The outlet conduit through which the gasoline is dispensed is marked by the numeral 23 and communicates at its upper end with the tank 4 through the bottom 5, the conduit terminating, externally of the support 1 in a spout 24 to which a hose (not shown) may be 80 attached, the numeral 34 designating a hook on the pedestal 1, over which hook the hose (not shown) may be suspended when not in use. A valve 25 is interposed in the outlet conduit 23 and is operated by a horizontally 85 slidable push pin 26.

The means for operating the valve 25 is in the form of a substantially vertical lever 27, the upper end of which is located outside of the pedestal 1, the lower end of the lever being 90 disposed inside of the pedestal, and the lever being fulcrumed intermediate its ends upon the pedestal, as shown at 28. A spring 29 is attached to the pedestal 1 and bears on the lower end of the lever 27 to swing that end 95 of the lever outwardly and against the pedestal 1 as delineated in Figure 4 of the drawings.

The upper end of a stop lever 31 is interposed between the lower end of the operating 100 lever 27 and the push pin 26 of the valve 25. The stop lever 31 is provided at its lower end with a coin pan 32, the lever being fulcrumed intermediate its ends, as shown at 33, on the pedestal 1, for swinging movement in a plane 105 about at right angles to the plane in which the lever 27 swings. The upper portion of the stop lever 31 has a cam edge 35, adapted to cooperate with the operating lever 27 in a way which will be pointed out hereinafter.

110 A spiral chute 36 is located in the pedestal 1. The mouth at the upper end of the coin

chute 36 is designated by the numeral 37 in Figure 1 and is accessible from a point without the pedestal 1. The lower end of the coin chute 36 discharges into the coin pan 32 of the 5 stop lever 31. When the coin is dumped out of the coin pan 32, the coin passes into the hopper 38 which is located at the upper end of a pipe 39 discharging at its lower end into a coin receptacle 40 supported by and located 10 within the pedestal 1.

One end of a flexible element 41 is connected to the lower end of the operating lever 27. The flexible element 41 extends inwardly, and then downwardly around a guide pulley 15 42 on the bracket 20, the flexible element being continued downwardly around a guide pulley 43 on the bracket 30, the lower end of the flexible element being connected to a catch 44 having teeth 45, the catch being mounted 20 for vertical reciprocation, and for limited movement in a horizontal direction, within the guide 11.

Suppose that there is a measured charge in the tank 4. Suppose, also, that the stop lever 25 31 is in the position shown in Figure 6, the upper end of the stop lever being interposed between the lower end of the operating lever 27 and the push pin 26 of the valve 25. The guide pulley 43 is set far enough back, that is, 30 to the right in Figure 4, so that the lower end of the catch 44 tends to swing inwardly, and to rest against the outer end of the valve lever 9, below the teeth 45 of the catch 44. Because the upper end of the stop 31 is interposed between the lower end of the operating lever 27 and the push pin 26 of the valve 25, a person working the lever 27 from the outside of the pedestal 1 cannot cause the lower end of the lever 27 to engage the push pin 26.

Let it be supposed, however, that a coin is deposited in the chute 36, by way of the mouth 37 of the chute. The coin rolls downwardly along the chute 36, and ultimately arrives in the coin pan 32 on the stop lever 31. Under 45 the weight of the coin, the lever 31 is tilted so that the upper end of the lever no longer lies between the lower end of the lever 27 and the push pin 26. The lever 31, however, does not at this time tilt far enough to spill the coin 50 out of the coin pan 32. The reason why the lever 31 is permitted to hang with the coin in the coin pan 32 is that it is not desirable to have the upper end of the lever 31 to swing back immediately between the lower end of the lever 27 and the push pin 26, lest the operator, having deposited his coin, may not have sufficient opportunity to manipulate the lever 27 and obtain the measured quantity of gasoline for which he has paid.

The operator swings the lower end of the lever 27 inwardly, the upper end of the lever being accessible from a point without the pedestal 1. When the lower end of the lever 27 swings inwardly, the push pin 26 is operated, and a charge of gasoline flows outward-

ly through the pipe 23—24, from the tank 4, when the valve 25 is opened by the operation of the push pin 26. When the lower end of the lever 27 swings inwardly, the same cooperates with the cam edge 35 of the stop lever 31, and tilts that lever a little more, thereby dumping the coin out of the pan 32, the coin passing through the hopper 38 and the pipe 39 into the coin receptacle 40. When the lever 31 no longer is weighted by the coin, the 75 lever is in such a condition that it can swing back between the push pin 26 of the valve 25 and the lower end of the lever 27 as soon as the lever 27 is released so that it can move back into the position shown in Figure 4, 80 under the action of the spring 29.

When the lower end of the lever 27 is swung inwardly, that is, to the right in Figure 4, the flexible element 41 moves downwardly over the pulleys 42 and 43, one of the teeth 45 of the catch 44 engaging with the lever 9, because the pulley 43 is so located that the catch 44 tends to swing to the right in Figure 4. When the lever 27 is released, so that it can move back into the position of Figure 4, under the action of the spring 29, the flexible element 41 is drawn upwardly, one of the teeth 45 on the catch 44 cooperating with the lever 9 and opening the valve 8. When the catch 44 has been raised, and when the lever 9 has 90 swung upwardly far enough, the teeth 45 will clear the lever 9. When the valve 8 is opened by the lever 9, suction is created in the tank 4 through the pipe 7, and a new supply of gasoline or liquid is drawn into the tank 4, the valve 8 closing slowly, and the lever 9 ultimately arriving again in the position shown in Figure 4 of the drawings. When the valve 8 closes to cut off the suction, it places the upper portion of the pipe 7 in communication with the interior of the pedestal 1, thereby to vent the tank 4, this being a common application of a three-way valve.

The operator can open the door 2 and rotate the pinion 21 by way of the handle 22, the rack bar 16 being raised and lowered, and the slide pipe section 14 being raised and lowered. In this way, the operator, noting the scale 6 on the tank 4, and the relation between the scale and the upper end of the pipe section 14, can set the machine for the dispensing of the desired number of gallons. The gasoline finds its way into the tank 4 through the pipes 12 and 14, and any gasoline which may be discharged into the tank 4 will 100 flow back through the pipes 14 and 12.

What is claimed is:—

In a liquid dispensing device, a tank, a combined liquid supply and overflow pipe communicating with the tank, a suction conduit communicating with the tank, an outlet conduit communicating with the tank, a first valve in the outlet conduit, a second valve in the suction conduit and having a lever and a fulcrum therefor, an operating lever, means 125

for fulcruming the operating lever in such a position that a part of the operating lever may be engaged with the first valve, a stop member, means for mounting the stop member for movement into and out of the path of said part of the operating lever, thereby to prevent said part of the operating lever from operating the first valve, a catch having a bevelled tooth engageable with the lever of the second valve, a guide in which the end of the lever of the second valve operates, the catch being movable longitudinally in the guide, a flexible element on which the catch

is suspended directly, the flexible element being connected to the operating lever, means 15 for guiding the flexible element in such position that the catch will tend to swing transversely in the guide, against said end of the lever of the second valve, whereby the tooth will operate the lever of the second valve 20 when the catch moves upwardly and whereby the tooth will slide over the lever of the second valve when the catch moves downwardly.

In testimony that I claim the foregoing as my own, I have hereto affixed my signature.

WILLIAM C. APGAR.
